UNITED STATES PATENT OFFICE.

EDWARD A. RUMELY, OF LAPORTE, INDIANA, ASSIGNOR TO M. RUMELY COMPANY, OF LAPORTE, INDIANA, A CORPORATION OF INDIANA

CARBURETER.

1,055,084.

Specification of Letters Patent.

Patented Mar. 4, 1913.

Application filed January 10, 1910. Serial No. 537,202.

To all whom it may concern:

Be it known that I, EDWARD A. RUMELY, a citizen of the United States, residing at Laporte, in the county of Laporte and State 5 of Indiana, have invented a certain new and useful Improvement in Carbureters, of which the following is a specification.

My invention relates to improvements in carbureters, and one application of it is 10 illustrated in the accompanying drawings, wherein—

Figure 1 is a vertical section; Fig. 2 is a vertical section on the line 2—2 of Fig. 1; Fig. 3 is a horizontal section on the line 15 3—3 of Fig. 1; Fig. 4 is a vertical section showing the shutter in position for minimum power.

Like parts are indicated by the same letter in all the figures.

20 A is a shell which with the wall A¹ forms the mixing chamber A².

B is a hydrocarbon or fuel valve supplied from the pipe B¹ and provided with the nozzle B² which discharges into the mixing 25 chamber. C is a similar liquid or water valve provided with the supply pipe C¹ and with the nozzle C² which discharges into the mixing chamber.

D is a mixture discharge port and D¹ the 30 connection which leads thence to the engine.

E is the air supply port provided with a shutter which consists as here illustrated of a series of dove-tail slats E¹ E².

E² is a passageway leading to the air supply port.

35 F is a slide valve adapted to control as indicated the mixture discharge port and the air supply port and it is controlled in any desired manner or by any desired motive 40 power by means of the connecting rod F¹ which passes out through the case, F² being an aperture in the slide valve F.

I have spoken of hydrocarbon and water valves but the essential point is that I connect to the mixer a hydrocarbon and a water supply pipe. The valve is only for the purpose of adjusting the size of the aperture but in each case the oil or water is drawn from the supply pipe by the vacuum in the 50 mixing chamber. It is that vacuum which causes the fluid to flow and by varying the vacuum the flow of fluid is varied. The arrangement of parts must therefore be such as to bring about this result. In other 55 words, the liquid supply pipes may be

worked without any valve in either of them, though in the convenient form of the device I employ, as illustrated, needle valves. The water supply is separately operative and may be dispensed with. The devices, whatever they are, whether needle valves or any other mechanism, should be adjusted so that the oil or fuel will flow with any degree of vacuum and so that the water will only begin to flow at a relatively high vacuum. 60 In other words, the two valves do not respond equally to the same vacuum. As the vacuum increases after the water begins to flow the increase in flow of water is more rapid than the increase in flow of fuel responsive to the increasing vacuum. 65

I have here illustrated an operative device but since the structure may be greatly varied without departing from the spirit of my invention, I wish my drawings to be taken as 75 in a sense diagrammatic. Not only may the proportions, size and relation of the several parts be greatly altered but a device very much different from the slat-formed shutter might be employed to provide a variably adjustable shutter or air port. 80

I have shown my invention as applied to a carbureter which is adapted to be supplied with both fuel and water, but the use of fuel and water under the conditions here set out and in the manner here described, is no part of my invention. It is the invention of another, applications on which are about to be filed. My invention has to do with, in the concrete form here shown, a sectional 90 shutter.

The use and operation of my invention are as follows: As the engine operates it draws its charge from and through the carbureter and because of the relation between the mixture discharge port and the air supply port a vacuum is formed in the mixing chamber. This vacuum draws hydrocarbon and water from their respective supply pipes. If now the parts be adjusted as indicated in Figs. 1 and 2 the valve in its lower position, leaving the mixture discharge port wide open, by a proper adjustment of the shutter and the fuel or water valve or either or both of them as the case 100 may be, the parts will ultimately assume a position where for maximum powers there will be a substantially perfect combustion. In view now, of the sectional character of the shutter in the particular form shown, 110

2

these several sections can be adjusted for each proportionate variation in power so that practically perfect combustion can be had for each successive position of the 5 valve. If the sections were infinite in number the adjustment could be made theoretically for each possible position. Of course for practical purposes a limited number of adjustable sections will suffice. On the other 10 hand, by the use of this sectional shutter or a proper calculation, a shutter with an edge of a certain shape or curve could be designed which, as respects any given engine, would give the desired results. In either 15 case there would be a variation of the effective area of the air inlet by varying increments and in the case of the sectional shutter or its equivalent it would be possible to make an adjustment for each of the several positions to bring about the desired result. The 20 shutter sections could be arranged so as to be held in their proper position by friction, but if desired, means for securing them in position when the adjustment has once been 25 made could be applied. In practice it would be probably best to leave the liquid opening always of the same effective area as that for which it was fixed at the maximum power. I have shown the sectional shutter and its 30 devices in connection with the air admission port but it is quite possible that a device operating along the lines suggested could be applied to the air admission or the mixture discharge or both.

35 For full load it will be understood that the valve F must be pushed down to its lowest position. The upper part of the air inlet port is then uncovered and the adjustable shutter sections which are then un- 40 covered must at that time be permanently adjusted for maximum load. As the valve rises the discharge opening and upper part of the air inlet are steadily decreased and by manipulating the shutter sections which are 45 covered in the position for maximum power, a suitable relation between the discharge and intake openings may be obtained for each successive position of the valve. Such 50 adjustments of the shutter sections which are from time to time uncovered as the valve rises, may be made each without in any way interfering with the adjustment previously made for the others for any previous position.

55 Water may be introduced in connection with the hydrocarbon since the introduction of water along with the fuel tends to increase the efficiency of the engine, the reason for this being that the water is broken down, 60 into its component parts of oxygen and hydrogen at the beginning of the power stroke when the temperature is very high, thus absorbing a large quantity of heat which would otherwise pass away into the cylinder walls 65 and then into the jacket. As the tempera-

ture falls the heat which was absorbed in this disintegration of the water is given off as the oxygen and hydrogen combine to again form water, and the water finally passes out with the discharged gases 70 deprived of a large portion of the heat which it absorbed at the beginning of the stroke. This leads to a more even distribution of the heat during the stroke and causes a more even pressure in the cylinder. The water, 75 which may be introduced with the hydrocarbon, is first heated during the inhalation stroke by the heat of the cylinder. It then absorbs some of the heat of compression during the compression stroke, probably being 80 vaporized. It then is further heated during the working stroke during which it may act as superheated steam or may be dissociated into its component parts, hydrogen and oxygen. If this occurs, the oxygen 85 is united with the excess carbon. In any case the temperature at the initial point of the power stroke will be decreased and this temperature decrease will continue until the oxygen and hydrogen again combine to 90 form water. Beyond this point the temperature and pressure will be greater than it would be without the previous addition of water. This results in an increase in thermodynamic efficiency by maintaining the 95 mean effective pressure at a higher point during the working stroke even though the initial pressure at the beginning of such stroke is thereby decreased.

It will be understood, of course, that my 100 invention is applicable to the use of any kind of hydrocarbon fuel such as oil, gasoline, alcohol and other similar fluids.

I claim:—

1. In a carbureter, a mixing chamber having a fuel inlet, a port for the discharge of the mixture and a port for the admission of air, in combination with a device for varying the effective area of one of the ports, said device containing a series of separately 110 adjustable sections.

2. In a carbureter, a mixing chamber having a fuel inlet, a port for the discharge of the mixture and a port for the admission of air, in combination with a device for varying 115 the effective area of the air admission port, said device containing a series of separately adjustable sections.

3. In a carbureter, a mixing chamber having a fuel inlet, a port for the discharge of the mixture and a port for the admission of air, in combination with means for varying the effective area of one of said ports at each of several positions without disturbing the area of such port so fixed for other positions to adapt such area for variations in power.

4. In a carbureter, a mixing chamber having a fuel inlet, a port for the discharge of the mixture, and a port for the admission of 130

- air, in combination with means for varying the effective area of the port for the admission of air at each of several positions without disturbing the area of such port so fixed for other positions to adapt such area for variations in power.
5. In a carbureter, a mixing chamber having a fuel inlet, a port for the discharge of the mixture and a port for the admission of
- 10 air, in combination with a valve for varying the area of the air admission port and a sectional shutter for varying the area of the air admission port.

6. In a carbureter, a mixing chamber having a fuel inlet, a water inlet, the two adapted so as to respond to different degrees of vacuum, a port for the discharge of the mixture, and a port for the admission of air, in combination with means for varying the effective area of one of the ports by varying 15 increments.
